CIGARETTE DISPENSER

Aribert J. Lehmann, New York, N. Y.

Application January 4, 1954, Serial No. 28,332

Term of patent 3½ years

(Cl. D85—2)

To all whom it may concern:

Be it known that I, Aribert J. Lehmann, a Swedish subject but having declared my intention of becoming a citizen of the United States, residing at 2 Broadway, in the county of New York and State of New York, have invented a new, original, and ornamental Design for a Cigarette Dispenser, of which the following is a specification, reference being had to the accompanying drawing, forming part thereof.

In the drawing

Fig. 1 is a top view of a cigarette dispenser showing my new design; and illustrating the same in closed position;

Fig. 2 is a side view of the cigarette dispenser shown in Fig. 1;

Fig. 3 is a front view of the cigarette dispenser shown in Fig. 1;

Fig. 4 is a rear view of the cigarette dispenser shown in Fig. 1;

Fig. 5 is a fragmentary sectional view taken substantially along the line 5—5 of Fig. 1; and Fig. 6 is a front perspective view of the cigarette dispenser illustrating the same in open position.

I claim:

The ornamental design for a cigarette dispenser, substantially as shown.
